UNITED STATES PATENT OFFICE.

THOMAS SPENCER, OF PHILADELPHIA, PENNSYLVANIA.

ELECTRIC-ARC LAMP.

No. 927,010.

Specification of Letters Patent.

Patented July 6, 1909.

Application filed April 3, 1907. Serial No. 366,205.

To all whom it may concern:

Be it known that I, THOMAS SPENCER, of Philadelphia, in the State of Pennsylvania, have invented a certain new and useful Improvement in Electric-Arc Lamps, whereof the following is a specification, reference being had to the accompanying drawings.

My invention relates to lamps of the class wherein the arc is formed between the lower ends of two carbons which both point downwardly, and may be employed with particular advantage with carbons containing metallic salts, and characterized as "flaming" arc carbons.

It is an object of my invention to provide such a lamp with simple and efficient means for contemporaneously controlling the feeding movement of the carbons; springing the arc between them, and preventing excessive flaming of the arc by restricting the movement of the latter.

As hereinafter described, my invention comprises a lamp wherein the feeding movement of one of the carbons is determined by its lower end resting upon a stop with respect to which it moves only as it is consumed, and, the holder of said carbon is connected by a yoke with the holder of the other carbon, so that the movement of both carbons is controlled by said stop which encounters but one of them. Said carbon which encounters the stationary stop is provided with a guide maintaining it in invariable angular relation with the lamp frame, but the other carbon is capable of lateral oscillatory movement toward and away from the controlling carbon to spring the arc; the oscillatory movement of said carbon being effected by a pivoted guide engaging its lower end and operatively connected by a rod with the movable core of a magnet coil.

As hereinafter described, the flaming of the arc is regulated and limited by two blow magnets and a magnetic bridge which short circuits the field of said magnets, so that said field is weaker nearer the normal location of the arc than in the region above the same.

My invention comprises the various novel features of construction and arrangement hereinbefore specified.

In the drawings; Figure I, is a side elevation of a lamp conveniently embodying my improvements. Fig. II, is a vertical sectional view of said lamp, taken on the line I, II, in the direction of the arrows marked on Figs. I, III and IV. Fig. III, is an in-

verted plan sectional view, taken on the line III, III, in Figs. I and II. Fig. IV, is a plan sectional view, taken on the line IV, IV, in Figs. I and II. Fig. V, is an enlarged vertical fragmentary sectional view of the arc striking mechanism shown in Fig. II, taken on the same plane as the latter, indicated by the line V, V, in Fig. VI. Fig. VI, is a vertical sectional view of said arc striking mechanism, taken on the line VI, VI, in the direction of the arrows shown in Fig. V. Fig. VII, is a fragmentary sectional view, taken on the line VII, VII, in Fig. IV. Fig. VIII, is a plan view of the insulating bushing shown in section in Fig. VII. Fig. IX, is a perspective view of the magnetic bridge shown in section in Fig. VII. Fig. X, is a plan view of the carbon holder shown in Fig. I. Fig. XI, is a fragmentary sectional view similar to Fig. V, but showing a modified construction.

In said drawings; the lamp frame comprises the cap 1, provided with the supporting loop 2, connected therewith by the cotter pin 3, extending through the insulator 4, and standards 5, on said cap. Said cap comprises four hangers 6, with which the frame plate 7, is rigidly connected by the screws 8, extending through the flanges 9, on the vertical webs 10, as shown in Fig. III. Said frame plate 7, is rigidly connected with the frame ring 11, at the bottom of the lamp, by the four rods disposed in two pairs 12, and 13, upon respectively opposite sides of the lamp and downwardly converged toward the central axis of the lamp, as shown in Fig. II. As shown in Fig. I, the rods of the respective pairs are parallel with each other, and the carbon holders 15, and 16, are mounted to slide on said rods between them. Said holders 15, and 16, are cross connected by the yoke comprising the sleeve 18, and opposite arms 19, which extend between pairs of rollers 21, and 22, in the respective holders, so that movement of one of said holders effects corresponding movement of the other holder, although they are permitted to approach and recede with respect to each other, in accordance with their position, on said frame rods 12, and 13. Said rollers 21, and 22, are carried by respective bearings 24, and 25, which are loosely fitted to said rods 12, and 13, and provided with pivot lugs 26, and 27, which bear upon said rods, so that said holders are capable of slight oscillatory movement thereon. Said carbon

holders 15, and 16, respectively comprise carbon sockets 30, and 31, which are split as indicated in Figs. I and II, so as to resiliently engage the upper ends of the respective carbons 32, and 33. It may be observed that said carbons are of respectively different diameters, the positive carbon 33, being larger than the negative carbon 32, and the proportion between the diameters of said carbons being such that they are respectively consumed at the same rate, in the arc gap 34, between their lower ends, when fed toward each other at the same rate.

The negative carbon 32, is provided with the stationary guide 35, secured in rigid relation with the frame ring 11, by the screws 36, but insulated therefrom by the mica 37. Said guide 35, co-operates with the rods 12, to maintain the carbon 32, in invariable angular relation with the central axis of the lamp, and determines its path of movement with respect to the stop 39, upon which it rests as shown in Fig. II. Said stop 39, being subjected to erosion by the action of the arc at said gap 34, is made a rotary disk so that its region of contact with the carbon 32, can be maintained substantially constant in relation to the path to which said carbon is limited by the guide 35. Said disk 39, is preferably copper and mounted on the stud shaft 40, so that it may be turned by hand, by the lamp trimmer, to present a fresh surface for contact with the carbon 32, as required. The cotter pin 41, and washer 42, detachably retain said disk 39, on the shaft 40, and, the latter is carried by the bracket 45, which is maintained in rigid relation with the frame ring 11, by the screws 46, but is insulated from said ring 11, by the bushings 47. Said positive carbon 33, being free to oscillate to a limited extent upon the pivot lugs 27, in the holder 16, may be automatically brought into contact at its lower end with the carbon 32, or be separated from the latter as shown in Fig. II, so as to spring an arc between said carbons, as follows:—Said carbon 33, extends through the guide 50, which is carried by the lever 51, but insulated therefrom by the bushing 52. Said lever 51, is pivoted at 53, in the bifurcated end 54, of the rod 55, which is mounted for free vertical reciprocation in the tubular column 57, which latter forms a rigid part of the lamp frame, being secured at its upper end in the frame plate 7, as shown in Fig. II. Said lever 51, is provided with a projection 59, which engages the stationary abutment 60, formed by the edges of a recess in said column 57, as shown in Fig. V, or, by a screw stud 61, as shown in Fig. XI. Said rod 55, carries the solenoid core 62, which is connected therewith by the pin 63, entered loosely through the slot 64, in said rod, as shown in Figs. V, and VI. Said rod 55, also carries at its upper end the dash pot plunger

65, formed of graphite, secured by the nut 66, on the metal head 67, which is rigidly connected with said core 62, by the pin 68. Said head 67, is provided with the automatic check valve 69, which, during the downward movement of the rod 55, admits air through the port 70, to the dash pot 71, but during the upward movement of said rod prevents the admission of air through said port. Said dash pot 71, is carried by the flanged ring 72, which is held in place by the sleeve 73, of non-magneticable metal, which, with the annular disks 74, of magnetizable metal forms a spool for the solenoid coil 75. Said spool is rigidly secured on the frame plate 7, by the screws 76, shown in Fig. III, so that said coil 75, encircles the solenoid core 62, in operative relation therewith, as shown in Fig. II. It is to be understood that when the lamp is energized, said core 62, is raised by the magnetism of said coil 75, to the position shown in Fig. II; the speed of its upward movement being limited by the escape of air between said plunger 65, and the dash pot 71. Such movement of the core 62, raises the rod 55, and the lever 51, so that the latter is tilted to the position shown in Fig. II, by contact of its projection 59, with the abutment 60. Such tilting movement of the lever 51, may be variably limited by the set screw 79, shown in Figs. V, and VI, having a conical point which encounters the adjacent edge of said lever 51; it being understood that the extent of the tilting movement may be increased by withdrawing said screw 79, or decreased by inserting it. Said solenoid coil 75, is connected in series with the resistance coils 77, and 78, which as shown in Fig. II, are wound upon spirally grooved porcelain bobbins 80, supported by the rods 81, which are detachably held, by the nuts 82, in the cross bars 83, which, as shown in Fig. III, are detachably secured in rigid relation with the webs 10, of the frame plate 7, by the screws 84. Said carbons 32, and 33, extend through respective openings 85, and 86, in the porcelain bushing 87, shown in Fig. VIII, which is encircled by the magnetic bridge 88, shown in perspective in Fig. IX. Said bridge is conveniently formed of a punched strip of sheet iron, and retained between the brass frame ring 11, and the porcelain bushing 87, by the screws 90, shown in Fig. I, which are entered through the apertures 91, in said bridge, and impinge upon said bushing 87, so as to detachably retain the latter. When thus secured, the recesses 92, in the edges of said bridge are adjacent to the cores 95, of the blow magnet coils 96, which are located upon opposite sides of the spark gap 34, between the carbons 32, and 33, as shown in Fig. IV. Said cores 95, being rigidly mounted in lugs 97, in said ring 11, as shown in Fig. VII, are thus separated from said bridge. The effect of said magnetic bridge

88, is to make the magnetic field produced by said coils 96, weaker nearer to the normal location of the arc between said carbons 32, and 33, than above the same, so that the 5 tendency of the arc to flame upwardly is restricted by the progressively greater strength of the magnetic field in that direction. The effective extent of said resistance coils 77, and 78, may be adjustably varied by shifting 10 the clamps 98, and 99, longitudinally with respect to said coils, said clamps being secured in adjusted position, by the screws 100, and nuts 101; the latter being prevented from rotating by the bent ends 102, of said clamps to 15 which the leads are secured by screws 103.

The electric circuit through the lamp includes all of the coils in series relation with each other and the arc, as follows: The exterior positive lead 105, is detachably connected with the terminal 106, from which the lead 108, extends to the clamp ring 99, on the coil 78, whose end 109, is detachably connected by the nut 110, with the rod 111, which is rigidly mounted in the frame plate 7, but insulated therefrom. The flexible connector 113, extends from the binder 114, at the lower end of said rod 111, to the positive carbon holder 16, to which it is detachably secured by the binder 115. The circuit 20 thus includes the carbon 33, arc gap 34, carbon 32, carbon holder 15. The flexible connector 117, extends from the binder 118, on said carbon holder 15, to the binder 119, at the lower end of the rod 120, which latter is 25 rigidly secured at its upper end in the frame plate 7, but insulated therefrom. The lead 121, extends from said binder 119, to one of the blow magnet coils 96, which is connected in series with the other coil 96, by the lead 123. The lead 124, extends from the last coil 96, to the binder 125, on the end 126, of the resistance coil 77. The clamp 98, on said coil 77, is connected by the lead 128, with the binder 129, on the end 130, of the solenoid coil 75. The opposite end 131, of said coil 75, has the binder 132, connected by the lead 134, with the binder 135, on the switch lever 137, which is insulated from, but rigidly connected with, the shaft 138, having the handle 140; whereby said lever 137, may be turned into contact with or away from the negative terminal 121, which is detachably connected with the exterior negative lead 141.

It is to be understood that I do not desire 5 to limit myself to the precise details of construction and arrangement herein described, as various modifications may be made therein, without departing from the essential features of my invention, as defined in the following claims.

I claim:

1. In an electric arc lamp, the combination with a frame; of holders arranged to present two carbons in oblique relation to the vertical axis of said frame; means main-

taining one of said holders in invariable angular relation with said frame; means arranged to vary the angular relation of the other of said holders, by oscillation of the latter comprising a vertically reciprocatory 70 rod and a lever pivoted at the lower end of said rod and engaging the oscillatory carbon; a stationary abutment arranged to tilt said lever; means carried by said rod, arranged to limit the movement of said lever; 75 a magnet core carried by said rod; and, a magnet coil encircling said core in operative relation therewith, substantially as set forth.

2. In an electric arc lamp, the combination with a frame; of holders arranged to present two carbons in oblique relation to the vertical axis of said frame; means maintaining one of said holders in invariable angular relation with said frame; means arranged to vary the angular relation of the 80 other of said holders, by oscillation of the latter, comprising a vertically reciprocatory rod and a lever pivoted at the lower end of said rod and engaging the oscillatory carbon; a stationary abutment arranged to tilt 85 said lever; an abutment carried by said rod arranged to limit the movement of said lever; means arranged to adjust said abutment, to vary the movement of said lever; a magnet core carried by said rod; a magnet 90 coil encircling said core in operative relation therewith; a dash pot above said magnet; and, a plunger connected with said rod in operative relation with said dash pot, substantially as set forth.

3. In an electric arc lamp, the combination with a frame; of holders arranged to present two carbons in oblique relation to the vertical axis of said frame; means maintaining one of said holders in invariable 105 angular relation with said frame; means arranged to vary the angular relation of the other of said holders, by oscillation of the latter, comprising a vertically reciprocatory rod and a lever pivoted at the lower end of 110 said rod engaging the oscillatory carbon; an abutment arranged to tilt said lever; an abutment carried by said rod arranged to limit the movement of said lever; means arranged to adjust said abutment to vary the movement of said lever; and, means arranged to shift said rod, substantially as set forth.

4. In an electric arc lamp, the combination with parallel guide rods; of a carbon holder arranged to slide upon said rods between them, comprising bearings respectively engaging said rods; a tubular carbon socket; and, pivot lugs in said bearings intermediate of their ends, arranged for contact with said rods, to permit free oscillatory 125 movement of said bearings substantially as set forth.

5. In an electric arc lamp, the combination with a stationary tubular column; of a rod mounted to reciprocate in said column; 130

a lever pivotally connected with said rod and comprising means to engage a carbon; a stationary abutment in said column, being the edge of a recess in said column; and an abutment carried by said rod, arranged to limit the movement of said lever, substantially as set forth.

6. In an electric arc lamp, the combination with a stationary tubular column; of a rod mounted to reciprocate in said column; a lever pivotally connected with said rod and comprising means to engage a carbon; a stationary abutment in said column; a

projection on said lever arranged to contact with said abutment and tilt said lever; and, means connected with said rod, arranged to adjustably vary the extent of the tilting movement of said lever with respect to said rod, substantially as set forth.

In testimony whereof, I have hereunto signed my name at Philadelphia, Pennsylvania, this 2nd day of April, 1907.

THOMAS SPENCER.
